UNITED STATES PATENT OFFICE.

LE ROY MAZE, OF ST. LOUIS, MISSOURI, ASSIGNOR TO S. G. ADAMS STAMP AND STATIONERY COMPANY, OF ST. LOUIS, MISSOURI, A CORPORATION OF MISSOURI.

IMPRESSION-SEAL.

1,369,290.

Specification of Letters Patent. Patented Feb. 22, 1921.

Application filed October 11, 1920. Serial No. 416,194.

To all whom it may concern:

Be it known that I, LE ROY MAZE, a citizen of the United States, residing at St. Louis, Missouri, have invented a certain new and useful Improvement in Impression-Seals, of which the following is a full, clear, and exact description, such as will enable others skilled in the art to which it appertains to make and use the same, reference being had to the accompanying drawings, forming part of this specification.

My invention relates to a seal of the type ordinarily used by notaries and like officials in impressing the seals of legal documents and the like, the principal objects of my invention being to provide a relatively strong and substantial seal that is comparatively light in weight and having essential parts that are connected to the frame of the seal whereby they may be folded so that the entire structure while not in use occupies very little space, thereby enabling it to be conveniently carried in the pocket.

Further objects of my invention are, to generally improve upon and simplify the construction of those types of seals known as "pocket seals"; and, further, to provide a construction that is capable of being easily and cheaply manufactured and which can be readily manipulated to produce an impression on a legal document or seal, and, further to provide simple and efficient means for conveniently and firmly holding the seal while it is being manipulated.

With the foregoing and other objects in view, my invention consists in certain novel features of construction and arrangement of parts, hereinafter more fully described and claimed, and illustrated in the accompanying drawings, in which—

Figure 1 is a top plan view of a seal of my improved construction.

Fig. 2 is a side elevational view of a seal.

Fig. 3 is a front elevational view of a seal and showing parts thereof folded into position so as to bring the entire structure into a relatively small compass.

Referring by numerals to the accompanying drawings, which illustrate a practical embodiment of my invention, 10 designates the base portion of the frame of the seal, said base portion being in the form of a flat plate or disk and of such size as to receive the male portion 11 of the die and the latter

being preferably secured directly to the upper surface of said plate or disk.

Positioned a short distance above the plate or disk 10 is a horizontally disposed block 12 that forms a part of the one-piece frame and one end of this block is connected to the edge of the plate or disk 10 by a relatively wide curved member 13, the latter being reinforced by means of a centrally arranged rib such as 14. This construction provides a strong and substantially one-piece frame for the seal and carried by said frame are the various operating parts of the structure.

Formed integral with the plate or disk 10 and the underside of member 14 are depending lugs 15, the same being perforated horizontally in order to receive pintles 16 that are formed integral with and project inwardly from the upwardly projecting ends of a longitudinally disposed plate 17 and which latter performs the functions of a handle which may be grasped between the thumb and fingers when the seal is used.

The undersides of the lugs 15 are made flat in order that they may rest on a flat surface such as the top of a desk or table and thereby support the entire device in an upright position, as illustrated in Fig. 3.

Arranged for operation through a vertically disposed aperture that is formed through block 12 is a short screw rod 18, the lower end of which carries a die 19 that cooperates with die 11 and said die 19 is guided in its movements toward and away from die 11 by means of pins 20 which latter are seated in die 19 and operate through suitably located apertures in block 12.

Hinged in any suitable manner to the upper end of screw rod 18 is an elongated plate 21 that is adapted to be engaged by the thumb and fingers when screw rod 18 is to be rotated to move die 19 toward or away from coöperating die 11.

As a result of this construction, when the seal is not in use, the plate 21 can be swung or folded downwardly into a substantially horizontal plane, as illustrated in Fig. 3, and thus the entire device can be folded into compact form, thereby permitting it to be conveniently carried in the pocket or to be packed into a comparatively small space while in storage or transit.

The frame or body of my improved seal or that portion comprising the parts 10, 12

and 14 may be either cast, forged or stamped from suitable metal, and the parts 17 and 21 may be hinged or pivotally connected in any manner which will permit their being 5 easily and quickly folded against the body or frame of the seal, as illustrated in Fig. 3.

A seal of my improved construction is comparatively simple, is light, strong and durable, is capable of being easily and 10 cheaply produced, and the parts that are used in manipulating the seal to produce an impression are arranged so as to be folded against the body of the seal with the result that the entire device occupies comparatively little space and can, therefore, be 15 conveniently carried in the pocket.

It will be readily understood that minor changes in the size, form and construction of the various parts of my improved seal 20 can be made and substituted for those herein shown and described, without departing from the spirit of my invention, the scope of which is set forth in the appended claims.

I claim as my invention:

25 1. An impression seal comprising a body, a die fixed thereto, a member arranged for movement toward and away from the fixed

die, a die carried by said movable member, a manipulating member hinged to the movable member, and a manipulating member 30 hinged to the body of the die.

2. In an impression seal, a body, a die fixed thereupon, a screw rod arranged for movement through a part of the body, a die carried by said screw rod and adapted to co- 35 operate with the fixed die, and a manipulating member hinged to said body.

3. In an impression seal, a body, a die fixed thereupon, a screw rod arranged for movement through a part of the body, a die 40 carried by said screw rod and adapted to co-operate with the fixed die, and a manipulating member hinged to said screw rod.

4. In an impression seal, a body, a die fixed thereupon, a screw rod arranged for 45 movement through a part of the body, a die carried by said screw rod and adapted to co-operate with the fixed die, a manipulating member hinged to the body of the die, and a manipulating member hinged to said 50 screw rod.

In testimony whereof I hereunto affix my signature this 29th day of September, 1920.

LE ROY MAZE.
